UNITED STATES PATENT OFFICE.

FRANK A. GAUGER AND ROY W. JOHNSON, OF MILWAUKEE, WISCONSIN, ASSIGNEES,
BY MESNE ASSIGNMENTS, TO TIME-O-STAT CORPORATION, OF MILWAUKEE, WIS-
CONSIN.

HEATER APPLIANCE.

Application filed January 16, 1922, Serial No. 529,732. Renewed October 27, 1926.

This invention relates to certain new and useful improvements in heater appliances and, while the same refers more particularly to that type of heater generally employed for supplying hot water to a household, it may be applied to any type of heater utilizing a fuel burner.

The present type of automatic heating device is subject to many objections among which are its expensiveness of construction and operation, and the dangers incidental thereto, in that should the pilot light become extinguished, a manipulation of the fuel control valve will permit the escapage of fuel, and as a result be a serious danger to the life and property of the household.

Hence this invention has for one of its objects to provide a device of the class described in which the burner proper will be incapable of connection with its source of fuel supply as long as the pilot light is extinguished.

Another objection to the present type of automatic household heating device is that it operates only for the period during which water is being drawn from the system or else remains in operation until someone manually disconnects the fuel supply.

It is, therefore, another object of this invention to provide a heater appliance having a time limit whereby the heater burner may be ignited and the burner extinguished after a predetermined time, the time limit being preferably under the control of the operator in order that different periods may be obtained.

Another object of this invention is to provide a device of the character described which is capable of actuation either at the heater or at some point remote therefrom.

A further object of this invention is to provide a device of the character described which is so designed and constructed as to be capable of application to heaters now in use by the drilling of but one hole in the casing wall thereof adjacent the burner and connecting the burner fuel supply through our improved valve, whereby cost of installation is reduced to a minimum and the services of a skilled mechanic eliminated.

A still further object of this invention is to provide a device of the class described

which is capable of operation for a predetermined time at the end of which the burner fuel supply is automatically disconnected. 55

A still further object of this invention resides in the provision of a device of the character described in which a thermostatically controlled valve prevents the retaining in open position of the burner fuel supply 60 valve in the event the pilot light should be extinguished.

With the above and other objects in view which will appear as the description proceeds, our invention resides in the novel construction, combination and arrangement of parts substantially as hereinafter described and more particularly defined by the appended claims, it being understood that such changes in the precise embodiment of the 70 hereindisclosed invention may be made as come within the scope of the claims.

In the accompanying drawings, we have illustrated one complete example of the physical embodiment of our invention constructed 75 according to the best mode we have so far devised for the practical application of the principles thereof, and in which:

Figure 1 is an elevational view of one of our improved devices as applied to a water 80 heating appliance, but a fragment of the water heating appliance being shown, and parts of the device being broken away and in section;

Figure 2 is a view partly in section and 85 partly in elevation illustrating the interior construction of our improved device, the upper portion of the thermostatic element being broken away;

Figure 3 is a fragmentary view, partly 90 in section and partly in elevation and taken through Figure 2 on the plane of line 3-3, and

Figure 4 is a view taken transversely through Figure 2 on the line 4-4. 95

Referring now more particularly to the drawings, 5 designates the casing of a water heating appliance which may be of conventional construction having a water coil 6 and a burner 7 so arranged that its flames 100 play on the coil, the burner being connected with a fuel supply line 8 by a pipe 9 which leads through our improved valve construction 10, to be later described. Valve 10

consists of a substantially cross-shaped housing or casing 11, the horizontal arms 12 and 13 of which form an inlet and outlet with which pipes 8 and 9, respectively, are connected. The valve inlet and outlet are separated by an intermediate partition 14 having a port 15 which registers with the upper arm 16 and the lower arm 17 of the valve casing. Arms 16 and 17 are bored throughout their length and projected through the bore of arm 17, with its inner end tapered and closing port 15, is a valve bushing or sleeve 18. The inner end of sleeve 18 is recessed and has ports 19 in its wall communicating with the outlet side of partition 14, the inlet and outlet being connectable through the sleeve recess. The inlet and outlet are normally disconnected by a valve 20 which seats against the inner peripheral edge of sleeve 18 and 20 has a stem 21 extended outwardly there-through for engagement with a valve operating mechanism, to be later described.

Escapage of fuel around stem 21 is prevented by suitable packing 22, which is preferably spring held in usual manner. The valve 20 is normally yieldably urged to engagement with its seat by a spring 23 confined within the bore of arm 16 between the valve head and a removable cap or plug 24 closing the outer end of the arm bore.

Laterally projected from one side of the valve casing is a casting 25 of substantially cup-shape, in the bottom of which is positioned a pilot tip 26 which is supplied with a constant volume of fuel by a bypass 27 communicating with the inlet side of the valve. Bypass 27 is readily adjustable to vary the size of the pilot flame by a set screw 28, as best illustrated in Figure 2. Extended laterally from casting 25 is a tubular stem 29 which affords means of attachment of our improved device to the heater appliance.

The heater appliance casing wall is preferably drilled or apertured adjacent burner 7 and stem 29 inserted therethrough and made fast by a nut 30. As best illustrated in Figure 1, the axis of the bore of stem 29 preferably traverses the top face of burner 7, and secured in the wall of casting 25 concentric with the stem bore is a flash jet plug 31. The flash jet is connectable with the outlet side of the valve by a passage 32 so that an inward movement of valve 20 will supply fuel to the flash jet plug, shooting a jet of fuel through the bore of stem 29 which is ignited by the pilot and plays on burner 7. Simultaneously with the opening of valve 20, burner 7 is connected with its source of fuel supply, as will be readily obvious, and the flash of flame from plug 31 ignites the burner.

Valve 20 is preferably operated by means capable of retaining the same in open position for any desired period of time, whereby 65 the operator may cause burner 7 to be lit only

for the time required and then be automatically extinguished without requiring further attention.

In the drawings we have illustrated a dash pot arrangement for performing this function which consists of a casing 33 having its upper end closed by a cap 34 and its lower end closed by a cap 35, said casing being secured in axial alignment with valve stem 21 by a substantially U-shaped bracket 70 member 36, the sides of which are in the form of clamps secured to bosses formed on cap 34 and stem 17. Cap 35 is provided with a cylinder 37 concentric with casing 33, the space between cylinder 37 and casing 33 80 being connected by a plurality of passages 38 which terminate in a well 39 in the bottom of cap 35, said well forming a seat for a ball valve 40 which prevents passage of fluid from the interior of cylinder 37 through 85 passages 38 but permits fluid to flow into the cylinder through said passages.

Mounted in cylinder 37 is a plunger or piston head 41, the stem 42 of which passes outwardly through a stuffing box or gland 43 and has a head 44 secured thereon. Head 41 is normally urged inwardly by a spring 45, coiled about stem 42 and confined between cap 34 and the piston head, and has a snug or sliding fit in the bore of the cylinder, the 95 base of the cylinder being counter-bored, as at 46, for a slight distance to permit free movement of the piston. The interior of casing 33 and cylinder 37 is filled with an oil or other suitable fluid so that a movement 100 upwardly of piston 41, against the action of spring 45, will permit the fluid to follow the piston and when the piston is released spring 45 will tend to return same to normal position, valve 40 preventing the escape of 105 fluid from behind the piston.

To insure the slow, steady return of the piston under action of spring 45, a bypass 47 is provided between the interior of cylinder 37 and the space between the cylinder 110 and casing 33 which may be adjusted by a set screw 48. The greater the distance piston 41 is moved away from the inner end of the cylinder, the longer the time required for its return to normal position and when 115 piston 41 reaches the counter-bored portion 46 of the cylinder the same rapidly descends under action of spring 45.

For manipulating piston 41, a sliding rod 49 is mounted in apertures formed in lugs 120 or ears 50 of the bracket member 36 which is connected with head 44 by a stem 51, rod 49 having a handle 52. In operation handle 52 is raised resulting in connecting head 44 with the end of stem 21 and moving valve 125 20 away from its seat. As the piston 41 slowly descends, valve 20 is moved toward closed position and as the valve nears its seat, piston 41 enters counter-bored portion 46 and is thus permitted to descend rapidly 130

and seat valve 21 with a snap to eliminate the slow extinguishing of the burner 7 and the dangers incidental to escapage of gas which would necessarily result from such an operation. As will be readily obvious, bracket member 36 may be graduated, as illustrated in Figure 1, in order that the operator may move handle 52 to any designation in order that the time during which the burner 7 remains lit may be readily regulated.

In order to eliminate any danger of the fuel supply being connected with burner 7, should pilot 26 be extinguished, and thus permit the escapage of unburnt gases, a thermostatic controlled valve 53 is provided which permits the liquid behind piston 41 to pass through a passage 54 into a tube 55 should the pilot light be extinguished and thus cause the piston to rapidly descend under action of spring 45, should it be raised by handle 52 or the remote control device to be hereinafter described.

Tube 55 is formed of brass, or any other material having a relatively high coefficient of expansion under temperature changes, and extends upwardly through an opening in casting 25 and has its upper portion enclosed by a cylinder or casing 56 which is closed at its upper end and provided with suitable vent openings. The upper end of tube 55 is closed by a cap 57 to which is adjustably secured the upper end 58 of a rod 59 of steel, or any other metal having a relatively low coefficient of expansion under temperature changes, and which extends throughout the entire length of tube 55 and has valve 53 secured to its lower end.

Valve 53, as best shown in Figure 2, normally seats against the peripheral walls of a port 60 which separates bypass 54 from the interior of tube 55 and is held against its seat as long as a flame is burning at pilot jet 26 and tube 55 is expanded. Should the pilot be extinguished, tube 55 cools and consequently contracts moving valve 53 from its seat and communicating tube 55 with the lower end of cylinder 37, as before described.

Should the appliance be located in the basement or at some other remote point, a cable 61 has one end connected with rod 49 and its other end connected with a crank or drum 62 on a shaft 63 which is rotatably mounted at any convenient point so that a rotation of the shaft by its handle 64 will raise rod 49 to operate the device, and in order that the operator may set the device for any desired period, handle 64 is provided with a pointer 65 which is adapted to be brought into alignment with any suitable time designations delineated on a dial 66.

As the operation of our improved device will be readily obvious from the foregoing description and the accompanying drawings, further discussion is deemed unnecessary.

What we claim as our invention is:

1. In a device of the class described, a fuel supply connectable with a burner, means for connecting the fuel supply with the burner, and means for flashing an igniting jet of flame toward the burner, said first named means automatically disconnecting the fuel supply from the burner after a predetermined period of operation.

2. In a device of the class described, a fuel supply connectable with a burner, a continually burning pilot light, means for connecting the fuel supply with the burner for a predetermined period, and means for flashing an igniting jet of flame toward the burner, the igniting jet of flame being lit from the pilot light.

3. In a device of the class described, a fuel supply connectable with a burner, a continually burning pilot light, means for connecting the fuel supply with the burner for a predetermined period, and means for flashing an igniting jet of flame toward the burner, said means being inoperative in the event the pilot should be extinguished.

4. In a device of the class described, a fuel supply connectable with a burner, a continually burning pilot light, means for connecting the fuel supply with the burner for a predetermined period, means for flashing an igniting jet of flame toward the burner, and thermostatically operated means for rendering said first named means inoperative upon extinguishing of the pilot light.

5. In a device of the character described, a fuel supply, a valve within the fuel supply and operable to connect the same with a burner, actuating means operable to sustain the valve open to connect the burner with the fuel supply for a predetermined time, manually operable means remote from the burner and remote from said valve and cooperable with the actuating means for moving the same to valve opening position, said actuating means permitting the closing of the valve after said time interval.

6. In a device of the class described, a burner fuel supply, a valve positioned within said supply for connecting the same with a burner, a dash pot member operable to move said valve to a position connecting the burner in a fuel supply, said dash pot member permitting the return of said valve to closed position after the elapse of a predetermined time interval, and means accelerating the return action of the dash pot member as it nears its limit of movement to effect quick closing of the valve.

7. In a device of the class described, a burner fuel supply having a control valve therein, dash pot means operable to retain the control valve open a predetermined period, said means including a plunger engageable with the control valve, and means imparting a quick action to the plunger.

- when the same nears its limit of movement.
8. In a device of the character described, a burner fuel supply, a control valve in the fuel supply, dash pot means operable to retain the control valve open a predetermined period, said means including a plunger engageable with the control valve, and means imparting a quick action to the plunger when the same nears its limit of movement.
10. 9. In a device of the class described, a burner fuel supply, a control valve in the fuel supply, dash pot means operable to retain the control valve open for a predetermined period, said means including a plunger cooperable with the control valve, a dial having periods of time delineated thereon, means connected with said plunger and cooperating with said dial whereby the same may be set to retain the fuel supply open any set period of time, and means accelerating the return action of the plunger as the same approaches the limit of the period to which the plunger has been previously set.
10. In a device of the class described, a burner fuel supply, a control valve in the fuel supply, manually operable means engageable with the control valve to maintain the same in open position, a time element cooperable with said means for retaining the same in valve opening position for a predetermined period of time, and means effecting quick closing of the control valve when the limit of said predetermined period of time is reached, a pilot burner, and means for effecting closure of the control valve when the pilot burner is extinguished irrespective of the manipulation of the manually operable means and of the adjustment of the time element.
40. 11. The combination with a burner and a fuel supply conduit therefor, of a valve interposed in said conduit, spring means tending to seat said valve, cable means manually operable from a distant point of control for opening said valve, and a time element operatively associated with said cable means for holding said valve in open position for a predetermined time and for automatically effecting quick release and closing thereof at the expiration of such time.
12. In a device of the character described, a fuel supply, a valve within the fuel supply and operable to connect the same with a burner, means normally urging the valve to closed position, means operable to sustain the valve open against said closing means to connect the burner with the fuel supply for a predetermined time and permitting the quick closing of the valve by its closing means after said time interval, a pilot burner and a thermostatic control influenced by the pilot burner to effect closure of the valve when the pilot burner is extinguished.
60. 13. The combination with a gas burner and housing therefor having an aperture
- therein adjacent said burner, of a gas appliance comprising a casing having a passage therethrough, a spring actuated valve in said passage for opening and closing the same, a pilot burner carried by said casing, thermo-responsive means associated with said pilot burner, means interposed between said thermo-responsive means and said valve for rendering the operation of the latter dependent upon that of the former, means for attaching said casing to said burner housing to operatively position said pilot burner with respect to the aperture of the housing and to the main burner, said housing having inlet and outlet openings for connecting said passage with the gas supply and said main burner respectively and also having an opening for connecting the pilot burner with the gas supply.
14. The combination with a gas burner and housing therefor having an aperture therein adjacent said burner, of a gas appliance comprising a casing having a passage therethrough, a spring actuated valve in said passage for opening and closing the same, a pilot burner carried by said casing, thermo-responsive means associated with said pilot burner, means interposed between said thermo-responsive means and said valve for rendering the operation of the latter dependent upon that of the former, means for attaching said casing to said burner housing to operatively position said pilot burner with respect to the aperture of the housing and to the main burner, said casing having inlet and outlet openings for connecting said passage with the gas supply and said main burner respectively and also having an opening for connecting the pilot burner with the gas supply, all of said parts aforementioned as constituting said appliance being assembled as a unitary structure bodily attachable in operative position.
15. The combination with a burner and a supply conduit therefor, of a valve interposed in said conduit, spring means normally tending to seat said valve, cable means manually operable from a distant point of control for opening said valve, a time element operatively associated with said cable means for holding said valve in open position for a predetermined length of time and for automatically effecting quick release and closing of the valve at the expiration of such time, a pilot burner, and thermostatic means influenced by the pilot burner for effecting closure of the valve when the pilot burner is extinguished.
16. The combination with a burner and a supply conduit therefor, of a valve interposed in said conduit, spring means tending to seat said valve, a pilot burner, thermo-responsive means associated with said pilot burner, means interposed between said thermo-responsive means and said valve for

- rendering the operation of the latter dependent upon that of the former, cable means manually operable from a distant point of control for opening said valve, and
- 5 a time element operatively associated with said cable means for holding said valve in open position for a predetermined length of time and for automatically releasing said valve at the expiration of such time.
- 10 17. A control for burners comprising valve means controlling the supply of fuel to the burner, a time element operatively associated with the valve means and settable to maintain the valve means open for variable periods, and a manually operable control device remote from the burner and from the valve means and operatively associated with the time element, the time element and the manually operable control device having a
- 15 connection with the valve means whereby the valve means may be opened under the control of the manually operable control device and held in open position under the control of the time element for a predetermined time and yet permitted to close at the expiration of such predetermined time.
- 20 18. A control for burners comprising valve means controlling the supply of fuel to the burner, a time element operatively associated with the valve means and settable to maintain the valve means open for variable periods, and a manually operable control device remote from the burner and from the valve means and operatively associated with the time element and with the valve means whereby the valve means may be opened under the control of the manually operable control device and held in open position for a predetermined time and yet permitted to close at the expiration of such predetermined time under the control of the time element, and means other than the time element for effecting closure of the valve means when the time element releases the valve means at the expiration of the selected time interval.
- 25 In testimony that we claim the foregoing we have hereunto set our hands at Milwaukee, in the county of Milwaukee and State of Wisconsin.

ROY W. JOHNSON.
